UNITED STATES PATENT OFFICE.

FELIX W. LEINBACH AND CLARENCE A. WOLLE, OF BETHLEHEM, PENNSYLVANIA, ASSIGNORS TO SAID WOLLE.

PAPER BAG.

SPECIFICATION forming part of Letters Patent No. 242,662, dated June 7, 1881.

Application filed April 4, 1881. (No model.)

To all whom it may concern:

Be it known that we, FELIX W. LEINBACH and CLARENCE A. WOLLE, citizens of the United States, residing in Bethlehem, Northampton county, Pennsylvania, have invented an Improvement in the Manufacture of Paper Bags, of which the following is a specification. The object of our invention is to cut a tube of paper, without waste, into bag-blanks of such a character that when the primary fold is made in the bottom of the same said fold will have edges overlapping in the center and separated on the flaps, so that when the paste is applied and the finishing folds made a perfectly secure bottom will be formed, and the pasting of the bottom and sides of the bag together will be prevented. This object we attain in the manner hereinafter set forth, reference being had to the accompanying drawings, in which—

Figure 1 is a view of a tube from which a bag-blank has been cut in accordance with our invention; Fig. 2, a view of the blank after the primary fold has been formed on the bottom of the same; and Fig. 3 a view of the blank after the primary fold has been pasted, prior to the formation of the finishing folds.

On reference to Fig. 1 it will be observed that the tube is severed on curved lines *ff*, so that the mouth end of the blank is convex and the opposite or bottom end concave. On opening said concave end of the blank and folding back one side of the same on the line *x*, as usual, to form the primary fold, the edges *y y* will overlap each other between the lines *a a*, which define the extent of the bottom of the bag, and a space will intervene between said edges outside of these lines—that is to say, those portions which are afterward folded over on the lines *a a* to form the finishing flaps and complete the bottom. (See Fig. 2.) When paste is applied to the primary fold, as shown by the shading in Fig. 3, it cannot gain access to those portions of the tube which afterward form the sides of the bag, as these portions lie

beneath that part of the fold between the lines *a a*, and are protected by the overlapping edges, so that all risk of pasting the sides and bottom of the bag together is overcome.

Owing to the separation of the edges *y y* on those portions of the fold which are to form the finishing flaps, all three of the leaves *b*, *b'*, and *d* of said flaps receive paste, so that when they are folded over on the bag-bottom a close union of the three leaves with the bottom is effected, and no openings are presented through which the contents of the bag can leak.

It will be observed that by this method of cutting the tube into blanks the desired overlapping and separation of the edges of the primary fold of the bag-bottom is attained without waste of material; and it will be evident that the same result can be attained by severing the tube on lines inclined in opposite directions from the center to the edges of the tube, as indicated by the dotted lines *m* in Fig. 4.

We claim as our invention—

1. The mode herein described of cutting a tube of paper, without waste, into bag-blanks, the primary folds of which will have edges overlapping in the center and separated on the flaps, said mode consisting in severing the tube on lines curved, or inclined in reverse directions, from the center to the opposite edges of the tube, as set forth.

2. A bag-blank having its opposite ends curved, or inclined in reverse directions, from the center to the opposite edges, the bottom end being the reverse of the mouth end, as specified.

In testimony whereof we have signed our names to this specification in the presence of two subscribing witnesses.

FELIX W. LEINBACH.
CLARENCE A. WOLLE.
